UNITED STATES PATENT OFFICE.

WILLIAM FREDERICK CHRISTIANSEN, OF CHICAGO, ILLINOIS.

DESIGN FOR A CHAIR OR SIMILAR ARTICLE.

Application filed November 26, 1928. Serial No. 29,033. Term of patent 3½ years.

To all whom it may concern:

Be it known that I, WILLIAM FREDERICK CHRISTIANSEN, a citizen of the United States, residing at Chicago, in the county of Cook and State of Illinois, have invented a new, original, and ornamental Design for a Chair or Similar Article, of which the following is a specification, reference being had to the accompanying drawing, forming a part thereof.

The figure is a perspective view of a chair or similar article showing my new design.

I claim:

The ornamental design for a chair or similar article as shown.

In witness whereof, I hereunto subscribe my name, this 14 day of November, 1928.

WILLIAM FREDERICK CHRISTIANSEN.
